UNITED STATES PATENT OFFICE.

LESTER C. LEACH, OF FRAMINGHAM, MASSACHUSETTS, ASSIGNOR TO DENNISON MANUFACTURING COMPANY, OF FRAMINGHAM, MASSACHUSETTS, A CORPORATION OF MASSACHUSETTS.

RUFFLED CRÊPE PAPER.

Application filed September 22, 1923. Serial No. 664,245.

To all whom it may concern:

Be it known that I, LESTER C. LEACH, a citizen of the United States of America, and resident of Framingham, in the county of Middlesex and State of Massachusetts, have invented new and useful Improvements in Ruffled Crêpe Paper, of which the following is a specification.

The object of the invention is to provide ordinary crêpe paper or other crêpe material with ruffles to enhance the decorative effect, to form the ruffles in the crêping process, to hold the ruffles in ruffled condition by the crêping of the material adjacent the ruffles without stitching the other fastening means (although such means may be employed if desired), to form the ruffles integrally with the body of the paper, to form a ruffled sheet of crêpe material which in use has little if any greater tendency to stretch than ordinary crêpe material, notwithstanding the ruffles, and generally to improve the appearance and construction of crêpe paper and the like.

For the purpose of illustrating the genus of the invention, two concrete embodiments are illustrated in the accompanying drawing in which:

Fig. 1 is a front view of a portion of a ruffled sheet of crêpe material;

Fig. 2 is a rear view of a portion of the sheet;

Fig. 3 is an edge view of a portion of the sheet;

Fig. 4 is a diagram illustrating the method of manufacturing the sheet;

Figs. 5 to 8, which correspond to Figs. 1 to 4 respectively, illustrate another form of the invention; and

Fig. 9 is a diagram illustrating another stage of the process of manufacture.

The particular embodiment of the invention illustrated in Figs. 1 to 3 comprises a sheet of material crêped transversely as indicated at 1 and having rows of ruffles 2 extending longitudinally thereof. The rows of ruffles are interconnected with the crêped portion of the sheet along their center lines 3 as hereinafter described, the free ends of the ruffles extending laterally to each side of the center lines 3.

The modified form of the invention shown in Figs. 5 to 7 comprises a sheet having longitudinal rows of ruffles 11 and being

transversely crêped intermediate the ruffles 55 as indicated at 12. In this form the ruffles of each of the double rows 11 are interconnected with the sheet along their outer edges with the free ends of the ruffles projecting toward each other.

The preferred method of forming the sheet shown in Figs. 1 to 3 is as follows. A sheet of tissue paper or other suitable material is folded longitudinally as shown in Fig. 4, each fold being in the form of a 65 pleat with the folded edges 4 substantially meeting. These folds are preferably folded as flat as possible so that the overlapping portions of the fold are in face contact (the overlapping portions being separated in the 70 figure for the purpose of appearance). After the sheet has been folded and pressed either by hand or by machinery the sheet is run through an ordinary crêping machine with the lower side of the sheet against 75 the crêping roll.

A suitable crêping machine is illustrated diagrammatically in Fig. 9 where 21 represents a roll of the material to be crêped, 22 a roll dipping in the tank of liquid 23 for wetting the paper, 24 a heated roll which bears against the roll 22. As the paper travels between the two rolls 22 and 24 it is first wet by the roll 22 and then the excess moisture is squeezed out as the 85 paper crosses the plane connecting the axes of the two rolls. As the paper travels with the roll 24 it is partially dried and after making a partial revolution with the roll it is stripped from the roll by the doctor 90 knife 25 which crimps or crêpes the paper as it leaves the roll.

In making the form shown in Figs. 1 to 3 the folded tissue paper passes through the crêping machine with its lower side (Fig. 4) 95 against the roller 24. Thus as the paper is stripped from the roll 24 by the doctor knife 25 portions 1 of the sheet which contact with the roll are crêped but the superposed portions 5 and 6 are left substantially uncrêped 100 since they do not contact with the roll and hence cannot adhere to the roll as required for crêping. The crêping of the juxtaposed folds 4 (Fig. 4) of the sheet results in a substantial intercrêping of the longitudinal center of the overlying portion 6 of the fold therewith, so that while the lateral portions 7 (Fig. 4) of the folds ruffle up, the longi-

tudinal center of the top layer 6 is intercrêped with the edges 4. This not only holds the longitudinal center of the layer 6 in the plane of the sheet as shown in Fig. 3 but this intercrêping ties together the crêped portions 5 on opposite sides of each row of ruffles. Consequently when the finished sheet is dried the junctions 8 (Fig. 2) between the juxtaposed folds 4 have substantially no tendency 10 to open unless the sheet is subjected to an abnormally strong transverse tension.

The form shown in Figs. 5 to 7 is made in substantially the same way as that above described except that the folded material is fed through the crêping machine upside-down, the lower side (Fig. 8) contacting with the roll 24. This results in the sheet being crêped throughout the widths between the folds 13 and also throughout the widths 15 between the lines where the folds 13 bear against the overlying portions of the sheet, that is between the lines 14—14, 15—15, etc. Along the lines 13—14 and 13—15 the folds 20 are intercrimped with the body of the sheet thus forming junctions 16 (Figs. 6 and 7) 25 the abutting edges of which are securely locked together by the intercrêping. The overlying portions 17 of the folds curl up in the form of uncrêped ruffles as shown in 30 Figs. 5 and 7.

From the foregoing it will be evident that the preferred embodiments of the invention have the following characteristics. The crêped widths (that is the widths between the junction lines 8 in Fig. 2 and between the junction lines 16 in Fig. 6) substantially meet along the bases of the ruffles and the meeting edges are intercrêped with the bases to hold the edges together and to 35 hold the ruffles in ruffled condition. In each embodiment one edge of margin of each fold is intercrêped with the sheet; thus, in the first embodiment the converging or abutting edges or margins 4 are intercrêped with 40 the portion of the sheet immediately thereover (Fig. 4) while in the second embodiment the outer or diverging folds 13 are intercrêped with the portions of the sheet 45 immediately thereover namely at 14 and 15 in Fig. 8. It will also be evident that the folds in each embodiment are double and that the folds of each embodiment comprise 50 two adjacent double folds reversed relatively to each other; for example, referring to the left-hand end of Fig. 4 the right-hand folds 4 and 7 constitute one double fold which is reversed with respect to the left-hand double fold 4—7, the folds 4 of the two 55 adjacent double folds converging or being directed toward each other and the folds 7 of the other pair diverging or being directed away from each other. In the first form the folds of pair 4—4 are intercrimped or intercrêped with the overlying portion of the 60 sheet while the folds of the other pair 7—7

are free and ruffled, whereas in the second form the folds of pair 13—13 (corresponding to the pair 7 in the first form) are intercrimped with the overlying portions of the sheet while the folds of pair 17—17 are uncrimped and ruffled. 70

I claim:

1. A sheet of crêped material having an integral row of uncrêped ruffles on one side thereof. 75

2. A sheet of material having a row of integral ruffles on one side thereof, the sheet being crêped transversely of said row to hold the ruffles in position. 80

3. A sheet of material having a row of integral ruffles on one side thereof, the sheet being crêped transversely on each side of said row. 85

4. A sheet of paper having alternate widths crêped and uncrêped respectively, the uncrêped widths being ruffled. 90

5. A sheet of paper having alternate widths crêped and uncrêped respectively, the uncrêped widths being folded and ruffled, and the crêped widths substantially meeting along the base lines of the ruffles. 95

6. A sheet of paper having alternate widths crêped and uncrêped respectively, the uncrêped widths being folded and ruffed, the crêped widths substantially meeting along the bases of the ruffles and the meeting edges being intercrêped with said bases to hold the edges together. 100

7. An article of the character described comprising a sheet of crêped material having an integral row of ruffles extending transversely of the crêpe, the ruffles being in part intercrêped with the sheet and in part free from the sheet. 105

8. A sheet of paper having a fold extending longitudinally thereof, the sheet being crêped transversely and one margin of the fold being intercrêped with the sheet. 110

9. A sheet of paper having a fold extending longitudinally thereof, the sheet being crêped transversely and one margin of the fold being intercrêped with the sheet, the other margin of the fold being free and ruffled. 115

10. A sheet of paper having a double fold providing a folded edge on each side of the sheet with three thicknesses between the folded edges, the sheet, including one of said thicknesses, being crêped transversely of the folds with one of said edges intercrêped with the sheet, the other edge being free and the other two thicknesses being ruffled. 120

11. A sheet of paper having two adjacent double folds reversed relatively to each other to provide a pair of converging folded margins on one side of the sheet and a pair of diverging folded margins on the other side, the sheet being crimped transversely of said folds with one pair of said 125 130

margins intercrimped therewith and the other pair of margins being ruffled.

12. The art of making ruffled crêpe paper which comprises impressing a double fold in the paper and then crêping the paper transversely of the fold, one edge of the double fold being intercrimped with the overlapping paper and the other edge left free.

13. The art of making ruffled crêpe paper **10** which comprises pleating uncrêped paper and simultaneously crêping the paper transversely of the pleats and intercrêping parts of the pleats with other parts of the paper.

Signed by me at Framingham, Massa- **15** chusetts, this 18 day of September 1923.

LESTER C. LEACH.
